United States Patent Office.

WYATT W. MILLER, OF SAFE HARBOR, PENNSYLVANIA.

Letters Patent No. 69,287, dated September 24, 1867.

IMPROVED FAGOT FOR BEAMS.

The Schedule referred to in these Letters Patent and making part of the same.

TO ALL WHOM IT MAY CONCERN:

Be it known that I, WYATT W. MILLER, of Safe Harbor, in the county of Lancaster, and State of Pennsylvania, have invented a new and improved Pile for Rolling Beams; and I do hereby declare that the following is a full, clear, and exact description thereof, which will enable others skilled in the art to make and use the same, reference being had to the accompanying drawings, forming part of this specification.

This invention relates to a new method for forming piles from which to roll large or small double-flange beams, such as are used in fire-proof buildings, roofs, bridges, &c.

Piles are made in the ordinary way, used only for the smaller sizes of beams, up to about nine inches in height. The larger sizes are rolled from special piles, and my invention is intended to represent the simplest form for a pile for such double-flanged beams. In order to roll large sizes of beams it is necessary to approximate in the pile to the form of beam to be rolled, and it is also necessary to so-construct the pile that it may be readily handled in charging in the heating-furnace, and drawing therefrom, and unless it is firmly put together it will not bear handling. In the annexed drawing my invention is illustrated—

Figure 1 being a side view of my improved pile, and

Figure 2 a vertical cross-section of the same, the line xx , fig. 1, indicating the plane of section.

Similar letters of reference indicate like parts.

On rolling an iron bar through the last groove of the rollers, I produce the same in the shape shown at a in figs. 1 and 2, which is a flat bar, provided with a flange, b , projecting from the centre of one face, as shown. These bars $a a$ are then, by any suitable device or mechanism, provided with holes, which are punched through the same at the required distances, and the bars are cut to the required length. The bars $a a$ form the top and bottom of the pile. The web is formed of one or more flat bars $c c$, which are arranged vertically between the bars $a a$, as shown, their thickness nearly corresponding with that of the flange b , as shown in the drawings. On each side of the bars $c c$ are arranged upright plates $d d$, which are rolled so as to have small flanges $d' d'$ along their upper and lower edges, as shown. The bars c and d are also cut to the proper length, and arranged in their respective places, and the whole pile is then held together by means of hook-headed bolts or rivets $e e$, which are passed through the holes in the bars $a a$, which are mentioned above.

For making a beam, a bar, a , is laid down flat, the bars $d d$ are then placed upon it, and between the latter are placed the bars $c c$, and then the top bar a is laid on top, and the two bars $a a$ are then secured to the flanges of the bars $d d$ by means of the hook-headed bolts or rivets. The whole pile is thus rendered solid and easily handled, and is then charged in a heating-furnace and brought to a welding heat preparatory to being rolled into a beam between rollers, the construction and operation of which may vary, and is not part of my invention.

What I claim as new, and desire to secure by Letters Patent, is—

The pile, constructed as described and shown, consisting of the bars a having flanges b , bars d having flanges d' , hooked bolts e , and the flat bars c , as and for the purpose specified.

WYATT W. MILLER.
